US00D893491S

(12) **United States Design Patent** (10) **Patent No.:** **US D893,491 S**
(45) **Date of Patent:** **** Aug. 18, 2020**

(54) **COMPONENT FOR AN ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Kristina A. Babiarz**, San Jose, CA (US); **Jeremy Bataillou**, San Francisco, CA (US); **Eugene Cheung**, San Francisco, CA (US); **Sean Stewart Corbin**, San Jose, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Stephen McClure**, San Francisco, CA (US); **Shin Nishibori**, Kailua, HI (US); **John Raff**, Menlo Park, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/660,480**

(22) Filed: **Aug. 21, 2018**

Related U.S. Application Data

(63) Continuation of application No. 29/576,408, filed on Sep. 2, 2016, now Pat. No. Des. 826,235, which is a (Continued)

Primary Examiner — Austin Murphy

(74) *Attorney, Agent, or Firm* — Sterne, Kessler, Goldstein & Fox, P.L.L.C.

(57) **CLAIM**

The ornamental design for a component for an electronic device, as shown and described.

DESCRIPTION

FIG. 1 is a bottom front perspective view of a component for an electronic device showing the claimed design; FIG. 2 is a bottom rear perspective view thereof; FIG. 3 is a front view thereof; FIG. 4 is a left side view thereof; FIG. 5 is a right side view thereof; FIG. 6 is a top view thereof; and, FIG. 7 is a bottom view thereof.

(Continued)

The broken lines in the figures show portions of the component for an electronic device that form no part of the claimed design.

1 Claim, 5 Drawing Sheets

Related U.S. Application Data

continuation of application No. 29/557,795, filed on Mar. 11, 2016, now Pat. No. Des. 765,661, which is a continuation of application No. 29/527,276, filed on May 18, 2015, now Pat. No. Des. 751,559, which is a continuation of application No. 29/508,579, filed on Nov. 7, 2014, now Pat. No. Des. 729,805, which is a continuation of application No. 29/434,891, filed on Oct. 17, 2012, now Pat. No. Des. 717,800.
